SASH BALANCE FOR DOUBLE HUNG WINDOWS

Emil M. Padjen, Citrus Heights, Calif.

Application December 7, 1951, Serial No. 260,500

3 Claims. (Cl. 292—74)

1

The present invention relates to a sash balance for double hung windows and it consists in the combinations, constructions and arrangements of parts herein described and claimed.

Generally there is provided a balance for double hung windows which consists of a channel plate freely mounted in each of the stiles of a window sash and which channeled member is urged outwardly by a pair of cams each of which is provided with a spring tensioning device having adjustable means for controlling the same. The construction is such that it will permit opening and closing of windows with ease regardless of the difference in size and weight of the window and regardless of expansion and contraction due to weather changes. A window sash equipped with the present invention will not rattle or require weather stripping nor will it jam when being raised or lowered.

It is accordingly an object of the invention to provide a novel adjustable sash balance for double hung windows.

Another object of the invention is the provision, in a device of the character set forth, of a novel spring actuated cam forming a part of the invention.

A further object of the invention is the provision of novel means for adjusting the tension of a spring forming a part of the invention which spring is adapted to urge outwardly the aforesaid channel member.

Another object of the invention is to provide a device of the character set forth which is simple in construction, inexpensive to manufacture and yet effective and efficient in use.

Other and further objects of the invention will become apparent from a reading of the following specification taken in conjunction with the drawing, in which:

Figure 1 is an exploded perspective view of an embodiment of the invention.

Figure 2 is a front elevational view of a bracket and associated mechanisms forming a part of the invention.

Figure 3 is a sectional view taken along line 3—3 of Figure 2.

Figure 4 is a sectional view taken along line 4—4 of Figure 2.

Figure 5 is a fragmentary sectional view taken along line 5—5 of Figure 1.

Figure 6 is a perspective view of a cam forming a part of the invention.

Figure 7 is a perspective view of a lifting arm forming a part of the invention, and

Figure 8 is a fragmentary plan view of a win-

dow sash and window jam illustrating an embodiment of the invention mounted therein.

Referring more particularly to the drawing, there is shown therein a window sash generally indicated at 10 and provided with stiles 11 and having a pair of vertically extending spaced grooves 12 cut therein, the faces between said grooves 12 being cut away at the upper and lower portions thereof to form pockets 13 and leaving 10 a centrally disposed block 14 between the pockets 13.

In each of the pockets 13 there is mounted a bracket generally indicated at 15 and having a rear wall 16 and a pair of outwardly extending side walls 17 which lie in spaced parallel relation to the sides of the pockets 13 and, in effect, form continuations of the grooves 12. The bracket 15 is provided with a cover plate 18 which extends sufficiently outwardly to embrace the upper or lower end of the sash 10, as the case may be, it being understood that the devices in the upper pocket 13 and in the lower pocket 13 are identical but inverted.

A screw 19 extends through the plate 18 and 25 is provided with a head 20 which is countersunk in the plate 18. The screw 19 also extends through a horizontal arm 21 which has integrally formed therewith a vertically dependent plate 22 at whose lower end is integrally formed an outwardly and slightly downwardly extending arm 23. The elements 21, 22 and 23 will together be referred to as a "pull arm" generally designated at 24. A nut 25 is threaded upon the lower portion of the screw 19 and a compression spring 26 surrounds the screw 19 and has its upper end 30 in abutment with the underside of the arm 21 and its lower end in abutment with the upper side of the nut 25.

The channel member generally indicated at 26a is provided with an outer wall 27 and a pair 40 of inwardly extending side walls 28 which latter are adapted to extend into the grooves 12 and between the members 17 and the sides of the recesses 13.

A pin 29 interconnects the sides 17 of the 45 bracket in spaced relation to the rear wall 16 thereof and a pin 30 likewise interconnects the walls 17 adjacent the forward edges thereof and immediately above the arm 23.

A cam member is generally indicated at 31 and 50 is provided with a collar 32 which surrounds the pin 30 and with an integrally formed forward lip 33 and an integrally formed rear lip 34. The lip 33 bears against the inner side of the wall 27 and the rear lip 34 bears against the outer side of the wall 27 while the rear lip

34 bears against the upper side of the wall 23 of the pull arm 24.

In operation, it will be apparent that the cams 31 act to urge the channel member 26a outwardly into contact with a window jamb 35 with which the sash 10 is associated and that the pressure exerted by the lips 33 against the channel member 26a is regulated by turning the screw 19 to thus regulate the tension of the spring 26 against the underside of the arm 21 and, accordingly the pressure against the underside of the lip 34 thus increasing or decreasing the pressure exerted by the lips 33. Since the heads 20 of the screws 19 lie within the plates 18, they are accessible at all times and the tension referred to may be regulated without disassembling the apparatus. It will also be apparent that when the jamb 35 and sash 11 expand or contract due to changes in temperature, that the side walls 28 of the channel member 26a will at all times be presented in the path of any passage of air between such sash and jamb which might otherwise occur. It will also be seen that the tension urging the channel members 26a outwardly will cause the sash 10 to be held in any selected position while at the same time being sufficiently yieldable in character to permit the sash 10 to be raised and lowered without difficulty.

While but one form of the invention has been shown and described herein, it will be readily apparent to those skilled in the art that many minor modifications may be made without departing from the spirit of the invention or the scope of the appended claims.

What is claimed is:

1. A sash holder adapted to be mounted in a window stile having a pair of spaced longitudinally extending grooves formed in its outer face and a recess interconnecting said grooves at their upper ends and a like recess interconnecting said grooves at their lower ends, said holder comprising an elongated channel member having its sides positioned in said grooves, and spring means in each of said recesses for urging said channel member outwardly from said stile, said means including a cam pivotally mounted in each recess and having an outwardly extending portion and an integrally formed inwardly extending portion, said outward portions bearing against the bight portion of said channel member, a vertical plate in each of said recesses, an outwardly extending lower arm formed integrally with the lower end of said plate, a like arm formed integrally with the upper end of said plate, said lower arm bearing against the underside of the inwardly extending portion of the cam, and a spring for urging said upper arm in an upward direction.

2. A sash holder adapted to be mounted in a

window stile having a pair of spaced longitudinally extending grooves formed in its outer face and a recess interconnecting said grooves at their upper ends and a like recess interconnecting said grooves at their lower ends, said holder comprising an elongated channel member having its sides positioned in said grooves, and spring means in each of said recesses for urging said channel member outwardly from said stile, said means including a cam pivotally mounted in each recess and having an outwardly extending portion and an integrally formed inwardly extending portion, said outward portions bearing against the bight portion of said channel member, a vertical plate in each of said recesses, an outwardly extending lower arm formed integrally with the lower end of said plate, a like arm formed integrally with the upper end of said plate, said lower arm bearing against the underside of the inwardly extending portion of the cam, a spring for urging said upper arm in an upward direction, and means for adjusting the tension of said spring.

3. A sash holder adapted to be mounted in a window stile having a pair of spaced longitudinally extending grooves formed in its outer face and a recess interconnecting said grooves at their upper ends and a like recess interconnecting said grooves at their lower ends, said holder comprising an elongated channel member having its sides positioned in said grooves, and spring means in each of said recesses for urging said channel member outwardly from said stile, said means including a cam pivotally mounted in each recess and having an outwardly extending portion and an integrally formed inwardly extending portion, said outward portions bearing against the bight portion of said channel member, a vertical plate in each of said recesses, an outwardly extending lower arm formed integrally with the lower end of said plate, a like arm formed integrally with the upper end of said plate, said lower arm bearing against the underside of the inwardly extending portion of the cam, a spring for urging said upper arm in an upward direction, and means for adjusting the tension of said spring, said means including a bolt extending vertically through said upper arm, a nut threaded upon the lower portion of the bolt, and a compression spring surrounding said bolt between said upper arm and said nut.
